US00D797674S

(12) **United States Design Patent** (10) **Patent No.:** **US D797,674 S**
(45) **Date of Patent:** **** Sep. 19, 2017**

(54) **ELECTRICAL CONTACT**

(71) Applicant: **EBARA CORPORATION**, Tokyo (JP)

(72) Inventor: **Matsutaro Miyamoto**, Tokyo (JP)

(73) Assignee: **EBARA CORPORATION**, Tokyo (JP)

(**) Term: **15 Years**

(21) Appl. No.: **29/533,317**

(22) Filed: **Jul. 16, 2015**

(30) **Foreign Application Priority Data**

Jan. 20, 2015 (JP) 2015-000932
Jan. 20, 2015 (JP) 2015-000933

(57) **CLAIM**

The ornamental design for an electrical contact, as shown and described.

DESCRIPTION

FIG. 1 is a perspective view observed from a plan side of a electrical contact showing my new design;

FIG. 2 is a perspective view observed from a bottom side thereof;

FIG. 3 is a front view thereof;

FIG. 4 is a rear view thereof;

FIG. 5 is a plan view thereof;

FIG. 6 is a bottom view thereof;

FIG. 7 is a right side view thereof; and,

FIG. 8 is a left side view thereof.
